Primary Examiner—Doris Clark(74) *Attorney, Agent, or Firm*—Kenyon & Kenyon LLP(57) **CLAIM**

The ornamental design for a bus shelter assembly, as shown and described.

DESCRIPTION

FIG. 1 is a front perspective view of a bus shelter assembly showing our new design.

FIG. 2 is a front elevation view thereof.

FIG. 3 is a right side elevation view thereof.

FIG. 4 is a top plan view thereof.

FIG. 5 is a rear elevation view thereof; and,

FIG. 6 is a left side elevation view thereof.
